HEAT-EXCHANGING BLOWER

William G. Patterson, Chicago, Ill.

Application November 21, 1946, Serial No. 711,399

1 Claim. (Cl. 257—244)

1
This invention relates to heat exchange devices and particularly to heat-exchanging blowers in which the heat transfer is between air or gas being pumped by the blower and a separate fluid medium passing through wholly enclosed spaces formed in the blower casing.

The main objects of this invention are to provide an improved heat-exchanging blower construction, to provide such a device having a greater efficiency of heat exchange between two different fluid mediums passing through the blower construction separately; to provide such a device which can be built as a simple, small compact unit; to provide such a device in which the blower casing or housing may be kept at a minimum size with respect to the blower impeller; and to provide an improved heat-exchanging blower of the centrifugal type which can more readily be incorporated as a radiator or evaporator in an air conditioning unit.

A specific embodiment of this invention is shown in the accompanying drawings in which:

Fig. 1 is a view in elevation of the front or discharge side of the improved heat-exchanging blower.

Fig. 2 is a side elevation of the same showing the air intake side of the device.

Fig. 3 is a sectional view as taken on line 3—3 of Fig. 2.

Fig. 4 is a sectional view as taken on line 4—4 of Fig. 3.

Fig. 5 is a fragmentary detailed view, as taken on line 5—5 of Fig. 4, showing the arrangement of external fins on the blower casing; and

Fig. 6 is a fragmentary sectional view at the air discharge or outlet opening of the device, as taken on line 6—6 of Fig. 4.

In the form shown in the drawings, the improved heat exchange unit comprises a paddle wheel type of volute or centrifugal blower, having a double-walled scroll, wholly enclosed within a housing spaced radially from the scroll and supported thereon, the housing having an air inlet at one side and supporting a motor at its opposite side for driving the blower impeller.

Referring particularly to Fig. 3, it will be seen that the blower casing comprises a scroll 1, which is a hollow or double-walled construction having the usual volute shape for centrifugal blowers, a side plate 2 which completely closes one side of the scroll 1 and an inlet plate 3 disposed at the opposite side of the scroll and having the usual central inlet opening 4 through which air is drawn into the interior of the blower through the

centrifugal action of the paddle wheel or impeller 5.

The housing which encloses the blower comprises a shell 6, which follows the volute curvature of the scroll 1, supported by angularly spaced axially extending ribs 7 which project radially from the blower scroll 1. The shell 6 is thus spaced from scroll 1 throughout its entire peripheral extent leaving a plurality of passages 10 between the ribs 7 through which air may flow in an axial direction from one side of the blower to the other, over the surface of the scroll 1.

A cowl 8 is provided on the side of the housing shell 6, adjacent the blower side plate 2, which cowl is shaped to the periphery of the shell 6 and curved radially inward from the margin of the shell to shroud or overhang the space between the shell and the scroll 1. The cowl thus serves as an inlet opening 8.1 for the device through which incoming air is first caused to engage the surface of the side plate 2 and is then directed to the spaced axial passages, extending across the outer or peripheral surface of the scroll 1, between the scroll and the shell 6.

The opposite side of the housing comprises a bell-shaped member 9, formed to fit the curvature of the shell 6, which is spaced axially from and completely encloses the inlet side of the blower. The closure member 9 is preferably formed with an inwardly curved central portion 10, centered on the axis of the rotor or impeller 5, which serves to direct the air, passing into the impeller from the spaces between the scroll and shell, toward the center of the opening 4 in the inlet plate 3 with a minimum of turbulence.

As shown, the impeller or rotor 5 is mounted fast on a shaft 11, which is journalled in suitable bearings mounted on the side plate 2 of the blower and in the central portion 10 of the housing closure member 9. The shaft 11 extends through the housing member 9 and is connected, by a suitable coupling 12, to the shaft extension of a motor 13 which is suitably mounted externally on the closure member 9, the motor mounting being arranged so that the motor shaft will be substantially aligned with the impeller shaft 11.

It will now be seen that upon rotation of the impeller 5 by means of the motor 13, the centrifugal action of the impeller will cause air to be drawn through the inlet opening 8.1 of the cowl 8 and the axial passages between the blower scroll 1 and housing shell 6, into the inlet opening 4 of the blower. This air will then be carried around the interior of the blower and its pressure

increased, due to the pumping action between the impeller and the volute scroll of the blower, until it reaches the discharge outlet 14 where the air will be discharged from the blower into a suitable duct system, not shown, or to atmosphere.

As shown in Figures 3 and 4, the double-walled scroll 1 provides a wholly enclosed fluid-tight passage or space 15, which extends around the entire periphery of the scroll from one side of the outlet 14 to the opposite side, and suitable inlet and outlet connections 16 and 17, which extend through the shell 6 and into the outer wall of the scroll, are provided for communication with the enclosed space 15 at its uppermost and lowermost points respectively. Also, as shown in Figures 4 and 6, suitable passages 18 are provided on each side of the outlet 14 for communication between the upper and lower ends of the enclosed space 15 within the walls of the scroll 1.

Thus a suitable heating or cooling medium may be caused to pass through the passage 15 within the walls of the scroll 1 at the same time that air is being pumped by the blower and, such air being in wiping contact with both inner and outer surfaces of the scroll, transfer of heat between the air and the heating or cooling medium passing through the hollow scroll will readily occur by conduction through the body of the scroll. Also, since the passage 15 is entirely enclosed the heating or cooling medium is maintained in a separate circuit and no leakage or mixing of that medium with the air pumped by the blower can occur.

In order to afford maximum conduction contact of the air handled by the blower with the body of the scroll 1 a plurality of fins or radial extensions of the scroll body are provided on both its inner and outer surfaces. The outer fins 19 are disposed to extend axially across the surface of the scroll in the spaces between the ribs 7, which support the shell 6 as shown in Figure 5, and these fins 19, together with the ribs 7, are given a slight curvature in the direction of rotation of the impeller 5, from the closed side of the blower casing, in order to minimize resistance to air flow and afford a greater length of contact with the air.

The fins 20 on the interior of the scroll 1 are arranged to extend circumferentially around the scroll, in the direction of rotation of the impeller 5, and these fins are spaced apart axially or from side to side of the scroll so as to provide a plurality of channels in which the air pumped by the impeller 5 will pass as it is thrown centrifugally against the inner surface of the scroll and pushed toward the discharge outlet 14. The inner fins 20 are arranged to maintain a uniform clearance from the tips of the rotor blades and their height is thus increased from the cut-off point in the blower casing to the discharge outlet in direct proportion to radii of the volute curvature of the scroll. In this manner the maximum of fin surface contact is had with the air as it is pumped through the blower casing.

It will now be seen that the herein described device provides a compact and efficient heat exchange unit for transfer of heat between air pumped by the blower and a separate medium which flows through a separate fluid-tight internal passage in the body of the blower scroll. Since the mediums between which the heat transfer is to occur are wholly separated from each other by the construction of the heat-exchanging blower, the device may be utilized for either heat-

ing or cooling of the air handled by the blower and with substantially any fluid heat conducting medium.

For example, the improved heat-exchanging blower may be used in conjunction with a heat pump or refrigerating apparatus for air conditioning purposes. For an air heating operation the hollow scroll of the heat-exchanging blower may be connected to a steam line or serve as the 10 condenser of a heat pump or refrigerating apparatus; and for cooling purposes the device may serve as the evaporator for a refrigerating apparatus or be connected to a cold water circulating system. In either case the refrigerant, or other 15 heat conducting medium, may pass directly through the hollow walled scroll of the blower without danger of leakage into the air being handled by the blower.

Also the length of the fins, both internal and 20 external, provides a sufficient total heat conducting surface to permit them to be spaced apart far enough as to create a negligible amount of resistance to the air flow. Thus the air leaves the blower outlet at the required velocity pressure 25 and static pressure without excessive rotor speed and power consumption, with a resultant quiet operation and lower maintenance cost.

The main advantages of this invention reside 30 in the simple construction of the device and its high efficiency as a heat exchanger. Other advantages are to be found in the compact unitary arrangement of the device whereby it may be readily mounted for use and easily connected into the circuit of a suitable heating or cooling medium. Still further advantages are to be found in 35 the adaptability of the improved heat exchange blower for use in air conditioning systems and particularly those self-contained air conditioning units for home or office use.

40 Although but one specific embodiment of this invention is herein shown and described, it will be understood that details of the construction shown may be altered or omitted without departing from the spirit of this invention as defined by the following claim:

45 I claim:

A heat exchange device comprising a hollow walled volute casing closed on one side and having an air inlet on its opposite side and a tangential air outlet, an impeller mounted for rotation within 50 said casing on the axis thereof, a plurality of radial fins extending axially on the outer surface of said volute casing, said fins being curved axially from the closed side of said casing in the direction of rotation of said impeller, and a housing 55 surrounding said casing and spaced therefrom, said housing having an air inlet on the side adjacent the closed side of said casing, and said casing having inlet and outlet conduits for a heat conducting fluid communicating with the space within its hollow wall.
